UNITED STATES PATENT OFFICE.

CECIL C. ABBOTT, OF HARBOR SPRINGS, MICHIGAN.

DEVICE FOR TRIMMING THE TIPS OF BILLIARD-CUES.

1,227,025.

Specification of Letters Patent. Patented May 22, 1917.

Application filed March 25, 1916. Serial No. 86,763.

To all whom it may concern:

Be it known that I, CECIL C. ABBOTT, a citizen of the United States, residing at Harbor Springs, in the county of Emmet and State of Michigan, have invented certain new and useful Improvements in Devices for Trimming the Tips of Billiard-Cues, of which the following is a specification.

10 This invention relates to devices for trimming the tips of billiard cues and has as its object to provide a device of this class which may be conveniently applied to the tip end of a billiard cue and readily manipulated to 15 symmetrically trim the tip thereof.

It is one aim of the present invention to provide a device of the class described, which may be readily employed to quickly trim down the margin of a leather cue tip 20 after the tip has been secured upon the tip end of the cue and to accomplish this result with but little exertion being required of the user of the device and with certainty that the tip when the trimming operation is complete, will be symmetrical in form.

Another aim of the invention is to provide a device of the class mentioned so constructed that the abrading element thereof may be readily renewed at an extremely low cost 30 and incidentally to permit of the substitution of abrading elements of different texture so that initially an abrading element of coarse texture may be employed for roughly cutting down the margin of the tip and after 35 this margin has been brought flush or substantially flush with the surface of the tip end of the cue, an abrading element of finer texture may be substituted and a smooth finish given the tip.

40 Another aim of the invention is to provide a device of the class described so constructed as to be adapted to receive practically any size of cue and trim any and all sizes equally symmetrically.

45 Another aim of the invention is to provide a device of the class described which may be manipulated to trim down a cue tip without imposing any torsional or lateral strain upon the tip tending to tear the same 50 from the end of the cue to which it is applied.

In the accompanying drawings:

Figure 1 is a perspective view of the device embodying the present invention, the

view illustrating also the tip end of a cue in 55 position about to be inserted into the trimming device.

Fig. 2 is a vertical longitudinal sectional view through the device, a cue being shown in elevation inserted therein.

Fig. 3 is a transverse sectional view on the line 3—3 of Fig. 2.

The device embodying the present invention comprises a tubular body 1 which is preferably, although not necessarily, formed 65 of metal and is of a diameter interiorly greater than the diameter of the larger sizes of billiard cues. At one end the body 1 is provided with an annular flange 2, the opening formed by which is indicated by the numeral 3 and this flange except for the opening 3 closes the said end of the body in the manner shown in Fig. 2 of the drawings. It is preferable that the wall of the opening 3, which wall is indicated by the numeral 4, be 70 transversely rounded so that the finish of a cue inserted through the opening will not be marred by contact with the said wall. Inasmuch as in the operation of the device the tip end of a cue is to be inserted through the 75 opening 3 and the device or the cue itself is to be reciprocated for the purpose of trimming down the tip of the cue in a manner which will presently be more specifically described, it will be understood that the opening 3 is of a diameter greater than the diameter 80 of the larger sizes of cues at their tip ends; although of a diameter less than the internal diameter of the tubular body 1 of the device. Furthermore it is to be observed 85 that the opening 3 is concentric to the inner surface of the said body 1.

The abrading element of the device is in the nature of a sheet of sand or emery paper indicated by the numeral 5, which sheet 95 is rolled upon itself and then inserted in the body 1 through that end of the body opposite the end at which the flange 2 is located. After such insertion of the abrasive paper into the body the roll will expand so as to constitute an abrasive lining for the interior of the body and as the best results may be secured by preventing longitudinal displacement of the paper 5 within the body the sheet is preferably of such dimensions that the roll thereof will be equal 100 in length to the length of the said body. In order to further prevent such displace-

ment and firmly hold the paper in place, a cap 6 is threaded on to the last mentioned end of the body as indicated by the numeral 7 and is provided with an opening 8 which 5 serves a purpose to be presently explained, the web of the cap bearing against the end of the roll of paper 5.

By reference to Fig. 2 of the drawings it 10 will be observed that in the use of the device the cue after having applied thereto the leather tip which is to be trimmed down, is inserted tip end first into the body of the device with the side of the cue resting against the wall 4 of the opening 3. The 15 device or cue itself is then reciprocated, the wall 4 of the opening 3 being maintained in contact with the side of the cue and the abrasive lining of the body 1 being maintained in contact with the tip of the cue 20 which is indicated by the reference letter T in the drawings. In such reciprocation of the device or the cue as the case may be, these two members are turned one about the other so that the tip T will be equally and 25 symmetrically trimmed as the operation progresses. It will be understood from the foregoing that initially relatively coarse sand or emery paper or cloth may be inserted within the body 1 and that after the 30 periphery of the tip has been brought flush with the tip end of the cue or more specifically the surface of the cue at its said tip end, this roll of abrasive material may be removed and one of finer texture substituted 35 therefore so as to complete the symmetrical trimming down of the said tip. If desired, the wall of the opening 8 in the cap 6 may also be rounded as in the case of the wall 4 of the opening 3 so as to permit of the 40 use of the device either end first. It will furthermore be understood that by providing an opening in the cap 6 the interior of the device may be viewed from either end of the device for the purpose of ascertaining 45 the condition of the abrasive element and without the necessity of removing the cap and subsequently removing the said element for the purpose of inspection.

Having thus described the invention, what is claimed as new is:

50

1. A device for trimming cue tips comprising a tubular body having an opening in one end of less diameter than the interior of the body through which the cue tip may be inserted and supported, and an abrasive lining within the body, the body being adapted to be reciprocated and rotated relative to the cue tip. 55

2. A device for trimming cue tips comprising a tubular body, an abrasive lining removably fitted within the body, and means for retaining the lining in the body, the body being provided at one end with an opening through which the cue tip may be inserted and being adapted for reciprocatory 65 and rotary movement relative to the cue tip.

3. A device for trimming cue tips comprising a tubular body, and a roll of abrasive material removably fitted within the body and lining the same, the body having 70 an opening in one end axially alined therewith and of less diameter than the bore of the body.

4. A device for trimming cue tips comprising a tubular body provided at one end 75 with an opening axially alined with the body, a roll of abrasive material removably disposed within the body and lining the same, said roll being removable through one end of the body, and means removably fitted 80 upon the said end of the body for closing the same and retaining the lining therein.

5. A device for trimming cue tips comprising a tubular body provided at one end with an opening of less diameter than the 85 body, a roll of abrasive material removably disposed within the body and lining the same, said roll being removable through an end of the body, and a cap removably fitted upon said end of the body and closing the 90 same, the said cap retaining the lining within the body and being provided with an opening.

In testimony whereof I affix my signature.

CECIL C. ABBOTT. [L.S.]
